CAR DOOR

Glenn H. Whittier, Los Angeles, Calif.

Application September 17, 1932, Serial No. 633,621

5 Claims. (Cl. 189—51)

My invention relates to car doors and particularly to doors for use in railway cars employed in handling bulk materials.

An object of the invention resides in providing a door for such cars which will readily withstand the pressure of the material within the car and which may be easily manipulated to open and close the opening in the car.

Another object of the invention resides in employing a pair of spaced guides disposed along the door frame and in employing a plurality of overlapping plates arranged in progressive order along said guides and adapted to be disposed in various overlapping positions to offer varying degrees of rigidity to resist the pressures of the various substances shipped in the cars.

An object of the invention resides in providing simple and effective supporting means for holding the plates in operative position and for latching the plates while so held.

Another object of the invention resides in forming guides with means providing laterally extending shoulders and in likewise constructing the plates with means forming laterally extending shoulders adapted to engage the shoulders of the guides and to hold the plates in position.

An object of the invention resides in constructing either the shoulder of the guides or the shoulders of the plate with cavities and the other thereof with lugs adapted to enter into the cavities and to hold the plates from lateral movement for preventing disengagement of the shoulders.

Another object of the invention resides in constructing the plates with flanges having openings therein to form said cavities and in constructing the guides with openings leaving shoulders and upwardly extending lugs therein adapted to engage the cavities in the plates.

A still further object of the invention resides in providing a pocket in the floor of the car door and in providing a plate serving as a sill for closing said pocket, said plate being hinged with respect to the floor and swingable substantially into the plane of the plates forming the closure.

An object of the invention resides in providing blocks slidable into a position behind said sill to hold the same in door closing position, said sill being swingable outwardly upon retraction of said blocks to permit the contents of the car in front of said door to flow outwardly therefrom.

A feature of the invention resides in constructing said blocks with inclined surfaces forming rests against which said sill may abut, said blocks

being laterally movable to permit of disengagement from said sill to release the same.

Other objects of the invention reside in the novel combination and arrangement of parts and in the details of construction hereinafter illustrated and/or described.

In the drawings:

Fig. 1 is a perspective view of a portion of a railway car illustrating an embodiment of my invention applied thereto.

Fig. 2 is an elevational sectional view taken on line 2—2 of Fig. 1.

Fig. 3 is a view similar to Fig. 2 showing the closure in altered position.

Fig. 4 is a view similar to Figs. 2 and 3 showing the closure completely open.

Fig. 5 is a fragmentary plan sectional view taken on line 5—5 of Fig. 2.

Fig. 6 is a fragmentary perspective view of a portion of the car frame and floor illustrating the construction of one of the blocks and its keeper.

Fig. 7 is a view similar to Fig. 6 showing the block removed from the keeper.

Fig. 8 is a detail sectional view taken on line 8—8 of Fig. 5.

Fig. 9 is another detail sectional view taken on line 9—9 of Fig. 5.

Fig. 10 is a perspective view of one of the blocks removed from its keeper.

Fig. 11 is a perspective view of a portion of the keeper.

Fig. 12 is a fragmentary perspective view of one of the posts of the door frame showing the construction for holding the plates supported.

My invention may be installed on any of the various types of railway cars used for handling bulk materials, such as grain, coal and similar raw materials. For the purpose of illustrating the application of my invention, an ordinary type of railway car has been shown, though it can readily be comprehended that the invention is applicable to any other type of railway cars.

The railway car illustrated has been indicated in its entirety at A and comprises side walls 10, a roof 11 and a floor 12, all of which is carried on supporting trucks (not illustrated). The wall 10 has an opening 13 therein whereby access may be had to the interior of the car. About this opening is provided a door frame 14 comprising a header 15 and two posts 16 and 17 (Fig. 5) supporting the same. A sliding door 18, provided with rollers 19 and 20 slides along a rail 21 so that the opening 13 may be closed from the exterior. The floor 12 consists of a number of longitudinally extending stringers 22 and 23, 55

which are supported through cross beams 24 situated at suitable intervals and braced through truss rods 25 in the usual manner. The floor 12 further includes a flooring 26, which is laid upon 5 the stringers 22 and 23 and which may be of suitable thickness to carry the various substances to be shipped in the car.

My invention proper consists of a door closure for the opening 13 in addition to the door 18, 10 which will withstand the pressure exerted by the material or commodity within the car, and which may be readily opened and closed to facilitate the loading or unloading of the car. This closure comprises a plurality of plates 27, 28, 29, 30, 31 15 and 32 which are progressively arranged in overlying position along two guides 33 and 34, which are shown in detail in Fig. 12. Both of the guides 33 and 34, being identical in construction, only the guide 34 will be described.

20 The guide 34 is constructed from two members, one an angle bar 35 and the other a Z-bar 36 both of which are attached to the post 17. The angle bar 35 is constructed so that the leg 37 thereof overlies the face 38 of the post disposed on the interior of the car, while the leg 39 thereof is disposed upon the face of the post within 25 the frame. This angle member serves as a shield for protecting the post and preventing injury thereto and at the same time forms a support for the various plates in a manner to be presently described. The Z-bar 36 is arranged so that one of the flanges 40 thereof is attached to the face 38 of post 17 in a position abutting against the leg 37 of angle 35. This Z-bar is further arranged so that the other flange 41 thereof overlies the leg 37 of angle 35 and forms in conjunction therewith a groove 42 serving as a guideway for the various plates 27, 28, 29 etc. These members may be secured to the post 41 through lag 30 screws or other types of screws, or the same may be bolted or attached thereto in any suitable manner.

The plates 27, 28, 29 etc. are of a length greater 45 than the width of the door opening 13 and are so constructed that the ends 43 thereof slide within the guideways 42 formed in the two guides 33 and 34. These plates are further constructed with the flanges 44 which extend outwardly from the plates proper and into the opening 13 of the frame. These flanges serve to stiffen the plates and resist the pressure applied to the plates upon the interior of the car from the materials stored in the car. The width of the guideways 40 are such that the plates may readily overlie one 50 another and so that the same may be moved into or out of position as required, without causing binding. When the plates are disposed in closing position, the same overlie one another as best shown in Figs. 2 and 3 with the various 55 flanges 44 projecting outwardly therefrom and on the same side of the closure. These plates in conjunction form a closure which I have indicated in its entirety at 45 and which as will presently become apparent, may be raised and lowered to cover more or less of the opening 13 and at the same time be made to reinforce one another so as to withstand greater or less pressure from the materials carried within the car.

For the purpose of supporting the plates 27 to 70 32 in position the various flanges 44 thereof are cut back as designated at 46 to provide outwardly projecting portions 47 disposed at the locality of the angles 35. The legs 37 of the angles 35 are constructed with a number of openings 51 75 and the posts 14 are notched as designated at 48

to provide recesses into which the projections 47 may extend. As many such openings as desired may be used to procure any degree of overlap of the plates. To accommodate the said projections the openings 51 extend into the legs 39 of the angles 35 as indicated at 49 whereby the projections 51 may be fully received within said openings and recesses and so that the various plates may lie snugly against the legs 37 of angles 35 which form the outermost side walls of the guideways 42. By means of this construction a shoulder 50 is formed upon the edge of each leg 37 of each angle 35 at each of the openings 51. In like manner a shoulder indicated at 52 in Figs. 2 and 3 is provided upon the underside of each of the projecting portions 47 which are adapted to rest upon the shoulders 50 and to support the various plates at the proper elevation.

In order to prevent the plates from being disengaged from the shoulders on which they are 20 supported a latch lug 53 is formed in the leg 37 of angle 35 at each opening which projects upwardly into the opening 51 and above the shoulder 50 thereof. This latch lug is adapted to enter into an opening or cavity 54 formed in the outwardly projecting portion 47 of the various plates. When the lugs 53 are received within openings 54 lateral movement of the plates with respect to the shoulders 50 on which they rest is prevented and the plates are securely held in position.

For the purpose of providing storage space for 30 retaining the various plates 27, 28, 29, 30, 31 and 32 when in disuse, a pocket is provided in the floor 12 which is indicated at 55 in Fig. 8. This pocket is constructed by removing a section of the floor at 56 and by providing an auxiliary stringer 57 immediately beneath the same for supporting said floor, which stringer is spaced from the stringer 23 a suitable distance to form the pocket 55 in which all of the various plates when 40 the same are properly nested may be housed. In place of the flooring removed a narrow strip 45 of wood 58 is provided which serves as a sleeper and which is laid upon the stringer 57. This strip follows along the side of the wall 10 of the car and is disposed between the two posts 13 and 14. The strip 58 provides a space 59 in which the various flanges 44 of the plates may extend when the plates are received within pocket 55. In order to receive the portions 47 of the various plates, 50 recesses are formed in the posts 16 and 17 at their lower ends and into which said parts project. This construction in conjunction with post 17 is shown in Fig. 5.

For closing the opening to the pocket 55 a sill 60 is employed which is constructed of plate material the same as the various plates forming the closure 45 and which is formed with an outwardly extending flange 61 corresponding to the flanges 44 of said plates. The sill 60 and its flange 61 are however of a length slightly less than the distance between the two posts 13 and 14 so that the same may be moved from a position closing the opening to the pocket 55 to a position giving access to the plates disposed therein. The sill 60 is preferably hinged to the floor so that the same may be swung from one position to the other. For this purpose pintles 63 are provided which are welded at the ends of the sill 60. These pintles are pivoted in leaf hinges 64 secured 70 to the flooring 26 of the floor 12. Through the agency of these pintles and hinges the sill 60 may be swung from the position shown in Fig. 4 in which the major portion of said sill lies flush with the surface of the floor 12 and in which the flange 75

61 thereof overlies the strip 58, to a position resting upon the floor 12. When in its former position the opening to the pocket 55 is completely closed and a smooth flush surface provided which 5 is in continuation of the floor. When in its other position the pocket 55 is opened and the various plates contained therein as shown in Fig. 8, may be manually elevated therefrom.

10 The sill 60 is so constructed that the same may be used as a part of the closure 45 for the opening 13, forming the lowermost plate of the group. For this purpose the hinge leaves 64 are arranged so that the axes thereof lie substantially in line with the flanges 41 of Z-bars 36 forming the 15 outer portion of the guideways 42. The openings 51 forming the supporting structure for the various plates are so arranged that the lowermost plate 32 may overlie the sill 60. When the parts are in proper position the various plates and sill 20 60 are disposed as shown in Figs. 2 and 3.

25 The sill 60 as previously described is narrower than the width of the opening 13 so that the same receives no support from the angles 35 as is the case with the other plates. To support the said sill I employ two blocks 65 which are disposed at the lower ends of the guides 33 and 34. These blocks are slidably retained within keepers 66 best illustrated in Figs. 6, 7, 9 and 11. The block 65 is formed with a beveled surface 67 which 30 forms a seat against which the ends of the sill 60 may rest when the block is projected outwardly beyond the angle 35. This block is further formed with a beveled surface 68 slightly offset from the surface 67 which forms a rest against 35 which the lower edge of the plate 32 may rest. When the blocks are in extended position the said blocks together with the sill 60 and the various plates, form a tight closure for the opening 13, preventing leakage of the substances 40 from the car through the opening.

45 The block 65 is slidably mounted in the keeper 66 as previously stated. This keeper consists of a back 69 and a base 70 connected together, which may be formed from a single sheet of material bent into the desired form. The back 69 is secured to the post 17 at the lower end thereof and the leg 37 of angle 35 may be cut away as indicated at 71 to receive said back. The base 70 of the back rests upon the floor 12 and extends 50 outwardly from the post. In conjunction with this structure a top 72 and a front 73 are employed which are attached to the back 69 and the bottom 70. The top 72 is constructed with a flange 74 which overlies the upper portion 75 of back 69 while the front 73 is similarly constructed with a flange 76 which overlies the marginal portion 77 of base 70. The top 72 and front 73 are secured to the back 69 and the bottom 70 through the flanges 74 and 75 which may be bolted or 55 screwed thereto. The block 65 as previously described, is slidable along the keeper 66 and may be projected outwardly beyond the same as shown in Fig. 6 so that the seat 67 is in position to support the sill 60 or the same may be moved to lie 60 completely within said keeper permitting the sill to swing as previously described.

65 For the purpose of holding the block 65 in proper position two nubs 78 and 79 are formed in the front 73 of the keeper 66 which are adapted 70 to engage into a depression 80 in the block 65. One end of the keeper 66 is formed open through which the block may be projected while the other end is provided with a closure 81 hinged to the top 72 at 82. This closure is arranged on an incline so that the same always remains closed 75

through gravity and may be opened when the occasion arises so that access to the block may be had for the purpose of cleaning or removal as desired.

80 The block 65 may be slid within the keeper 66 through direct engagement, if desired. However, for the purpose of facilitating movement thereof, the same is constructed at its forward face with a cavity 84 having a bar 85 extending across the same. A suitable hook may be hooked 85 in the cavity 84 behind the bar 85 whereby the block may be manually moved into or out of the keeper, as desired.

85 The use of my invention is as follows: In normal position the various plates forming the closure for the door are disposed within the pocket 55 as shown in Fig. 4 and the sill 60 in a position to overlie the opening to the same, said sill resting upon the strip 58 and the flange 61 of said sill 90 overlying the forward edge of the strip. When in such position the sill lies flush with the floor and the car has the appearance and utility of the ordinary box car. When it is desired to use the car for shipping grain or other similar materials frequently shipped in bulk, the sill 60 is 95 swung back to uncover the pocket 55 in the floor and inwardly of the opening 13. The various plate 27, 28, 29, 30, 31 and 32 are then raised by hand one at a time and slid along the two guides 33 and 34. Each plate is supported in 100 one of the recesses 51 as previously described, and the sill brought back into closing position. The plates are then arranged in such a manner that the lower ends of each of the plates overlie 105 the upper edges of the adjoining plates. Where a material having little pressure is being shipped, the plates may be slid apart as shown in Fig. 2 to substantially cover the entire area of the opening 13. Where, however, a material is to be 110 shipped which will exert appreciable pressure upon the door, the plates may be arranged in the position shown in Fig. 3 so that substantially two thicknesses of plates are provided throughout the vertical extent of the door. This gives double 115 strength to the closure and assists in more readily resisting the pressure of the material within the car. In either case the lower plate 32 is disposed above the floor of the car to leave a space therebetween. The sill 60 is used to close this space. After all of the plates have been elevated and 120 properly positioned the sill 60 is swung back into the position shown in Figs. 2 and 3 in which the same contacts with the lower edge of the plate 32. After the sill is so disposed the two blocks 65 may be projected outwardly to bring the 125 seats 67 into a position to support said sill. The closure is then completely closed and the car may be filled in the usual manner.

130 It is to be noted that in the filling of the car the upper plates may be grouped and supported in close proximity to one another at an elevation below their ultimate positions. As the car is filled the plates may be raised until the commodity or material is completely filled in the car. After the car has been filled the plates are 135 held in place through pressure of the material against the same and raising of the plates prevented through the action of the lugs 53 and the recesses 54 in the plates. When the car is to be 140 emptied the two blocks 65 are first shifted into the keepers 66 to clear the edges of the sill 60. As soon as this occurs the pressure of the grain forces the sill 60 into the position shown in Fig. 4 and the grain or other materials in the car may then flow out through the opening afforded by 145 75

removal of said sill. After the grain immediately in back of the closure has been removed, the sill 60 may be swung back into the car and the various plates of the closure lowered into the 5 then open pocket 55. Upon again closing the sill 60 the remainder of the grain may be removed from the car in the customary manner.

My invention is highly advantageous in that the structure may be used repeatedly, thereby 10 eliminating the usual expense in providing temporary wood closures which are destroyed after each use thereof. The closure members are conveniently located and when in disuse are completely out of the way. When desired for use the closure 15 may be quickly and easily erected. Any height of closure within the limits of the device may be procured and where materials exerting considerable pressure are to be shipped, the plates may be arranged to reinforce one another and to 20 supplement one another in resisting the pressure of the material. The manner of unlatching the plates is exceedingly simple and once the plates are in position, the same so remain until further manipulated. The device can be constructed at 25 a reasonable cost and without greatly changing the construction of the car. The pocket for the reception of the plates is open at the bottom so that in case any materials enter in the same, said materials will pass out through the pocket to 30 prevent jamming of the plates or operation of the device. The same car may be used for the shipment of any desired goods, such as is now the custom and the sill used for closing the pocket functions to protect the car and to render the 35 same more useful for its usual purposes.

Changes in the specific form of my invention, as herein disclosed, may be made within the scope of what is claimed without departing from the spirit of my invention.

Having described my invention, what I claim as new and desire to protect by Letters Patent is:

1. In a door structure for a railway car having a floor and a door frame including posts at the sides thereof, guides along the posts, a plurality of closure plates slidable at their ends in said guides and adapted to overlap each other in superimposed relation to form a closure of different heights for an upper portion of the door opening, each plate having an outwardly projecting flange at its upper edge, a sill hinged to the floor and swingable between the posts into an upwardly inclined position to close the lower portion of the door opening, keepers at the floor, 45 one at one side of the door frame and one at the other side thereof, blocks slidable in said keepers and movable into and out of position projecting into the door opening, each block having a beveled surface providing a rest for the adjacent end 50 of the hinged sill to brace said sill in its upwardly inclined position and having a second beveled surface, offset from said first beveled surface, providing a rest for the adjacent end of the lowermost closure plate in various elevated dispositions thereof, means on the guides adapted to cooperate with the flanges of said plates for swingably suspending the respective plates at selected elevations, the lowermost closure plate being adapted to swing by gravity into position against 55 said second mentioned beveled surfaces of said blocks and thereby lap the upwardly inclined sill and the remaining closure plates being adapted to swing by gravity into position one against the other.

2. In a door structure for a railway car hav-

ing a floor and a door frame including posts at the sides thereof, guides along the posts, a plurality of closure plates slidable at their ends in said guides and adapted to overlap each other in superimposed relation to form a closure for an upper portion of the door opening, a sill hinged to the floor and swingable between the posts into an upwardly inclined position to close the lower portion of the door opening, blocks slid 5 able into and out of the door opening at either side thereof and providing rests for the ends of the hinged sill to brace said sill in upwardly inclined position, means on the guides cooperating with said plates individually for swingably suspending the same across the door opening, the lowermost closure plate being swingable by gravity into position lapping and bearing against the upwardly inclined sill and the remaining closure plates being swingable by gravity into position one against the other.

3. In a door structure for a railway car having a floor and a door frame including posts at the sides thereof, guides along the posts, a plurality of closure plates slidable at their ends in said guides and adapted to overlap each other in superimposed relation to form a closure for an upper portion of the door opening, the floor having a pocket therein in continuation of said guides for the reception of the closure plates, a sill hinged to the floor and swingable between the posts from a position covering said pocket into an upwardly inclined position to close the lower portion of the door opening, means for bracing said sill in such inclined position, means on the guides cooperating with said plates individually for swingably suspending the respective plates across the door opening, the lowermost closure plate being adapted to swing by gravity into position lapping and bearing against the upwardly inclined sill and the remaining closure plates being swingable by gravity into position one against the other.

4. In a door structure for a railway car having a floor and a door frame including posts at the sides thereof, guides along the posts, a plurality of closure plates slidable at their ends in said guides and adapted to overlap each other in superimposed relation to form a closure of different heights for an upper portion of the door opening, a sill hinged to the floor and swingable between the posts into an upwardly inclined position to close the lower portion of the door opening, means for bracing said sill in such inclined position, means on the guides cooperating with said plates individually for swingably suspending the respective plates across the door opening, the lowermost closure plate being swingable by gravity into position lapping and bearing against the upwardly inclined sill and the remaining closure plates being swingable by gravity into position one against the other.

5. In a door structure for a railway car having a door frame including posts at the sides thereof, a plurality of plates adapted at their ends to overreach said posts and in superimposed overlapping relation to provide a closure for the door opening, said plates having outwardly projecting flanges at their upper edges, angles along the inner corners of said posts, each angle having corner slots formed therein and extending into both legs, corresponding slots in the two angles being adapted to receive opposite end portions of the flange of a plate, the upwardly facing edges of the angles at the slots providing rests for a flange and a support for the plate through 70 75

such flange, the legs of said angles in the plane of the door frame being formed with keeper lugs extending upwardly from said upwardly facing edges, said flanges being formed with apertures 5 therein to receive said lugs, the slots in said lugs and the apertures in said flanges freely receiving

said plate flanges and keeper lugs, respectively, whereby the closure plates are suspended swingably and thereby adapted by gravity to swing into position one against the other.

GLENN H. WHITTIER.
